(57) CLAIM

The ornamental design of a healthcare provider apron, as shown and described.

DESCRIPTION

FIG. 1 is a front view of an embodiment of a healthcare provider apron showing my new design;

FIG. 2 is a rear view of the healthcare provider apron of FIG. 1;

FIG. 3 is a front view of an alternate embodiment of a healthcare provider apron showing my new design; and,

FIG. 4 is a rear view of the healthcare provider apron of FIG. 3.

In the drawing figures, the broken lines at the top left and right edges of the apron represent unclaimed subject matter. Stitches are shown in long dashed lines.
